UNITED STATES PATENT OFFICE.

GEORGE N. DOWNS, OF CHICAGO, ILLINOIS.

CENTRIFUGAL MACHINE.

SPECIFICATION forming part of Letters Patent No. 397,051, dated January 29, 1889.

Application filed January 14, 1888. Serial No. 260,688. (No model.)

To all whom it may concern:

Be it known that I, GEORGE N. DOWNS, of Chicago, in the county of Cook and State of Illinois, have invented certain new and useful 5 Improvements in Centrifugal Machines; and I do hereby declare that the following is a full, clear, and exact description thereof, reference being had to the accompanying drawings, and to the letters of reference marked thereon, 10 which form a part of this specification.

This invention relates to improvements in separators or devices for extracting fluid from solid substances by centrifugal action.

The invention, which consists in the novel 15 devices and combination of devices herein shown, described, and claimed, is illustrated as embodied in a machine designed more particularly for use in laundries for the purpose of extracting water from clothes or other 20 articles preparatory to final drying, and will be better understood by reference to the accompanying drawings, in which—

Figure 1 is a side elevation of a machine embodying my invention. Fig. 2 is a central 25 vertical section of the same. Fig. 3 is a horizontal section taken on line 3-3 of Fig. 2. Figs. 4, 5, and 6 are sectional views illustrating modified forms of the movable shaft-bearing.

30 In said drawings, A is an outer tank or chamber supported upon the standards A', which standards are secured to a bed-plate, A², and are connected at their upper ends by arms or bars A³. Within the outer chamber or tank 35 is a perforated revolving cylinder or receptacle, B, in which are placed the clothes or other articles from which liquid is to be extracted. This cylinder B is rigidly secured to a vertically-arranged shaft, C, which shaft is provided 40 near its lower end with a belt-pulley, b, by means of which motion is communicated to it. The lower end of the shaft C is movably secured by a ball-and-socket bearing, as is shown in Fig. 2, the parts of which are constructed in detail as follows: The bed-plate A² is provided with a step or raised bearing, a, having a socket or recess corresponding in shape with the exterior surface of the ball or spherical enlargement c at the end of the shaft 45 C, and within which the latter may freely revolve. This bearing a is divided horizontally in two parts, as shown, to permit of the inser-

tion of the ball c, the upper part consisting of a cap, a', which may be secured to the lower portion by screw-threads, as herein shown, or otherwise. This construction permits of the 55 rotary motion of the shaft C, and also permits inclination of the shaft from its vertical position. The ball c and adjacent reduced part of the shaft will be made separate from the 60 main part of the shaft and attached thereto by a screw-joint or otherwise, to permit of the placing of the cap a' over the ball in assembling the parts.

As shown in Figs. 1 and 2, the upper end of 65 the shaft C is secured by a ball-and-socket joint to a second or auxiliary non-rotating shaft, C', the shaft C' having a spherical enlargement or ball, c', at its lower end, the exterior surface of which fits into a corresponding 70 recess in the two-part bearing c² c³, secured to the shaft C.

The auxiliary shaft C' is secured movably to the frame arms or bars A³ by the following devices: The arms A³ are united to a hollow 75 hub or ring, A⁴, located centrally over the shaft C. Within said ring A⁴ is mounted, by means of horizontal pivots d d, a separate horizontal ring, D, Fig. 3. Within said ring D is secured, by means of other horizontal 80 pivots, d' d', a tubular bearing, E, within which the shaft C' is mounted to slide longitudinally. The pivots d' d', connecting the ring D and bearing E, are arranged at right angles to the pivots d d, by means of which 85 the said ring D is supported upon the frame, so that the said ring D and its pivotal connections form a universal joint or connection between the shaft C' and the frame adapted to permit a free lateral movement of the 90 lower end of the shaft in every direction. The said shaft C', while constructed to slide freely in the tubular bearing E, is held from rotation therein by any well-known or suitable device for this purpose. As herein illustrated, the shaft C' is provided with a longitudinal groove, c⁴, which is engaged by a pin or lug, e, upon the said bearing E. Between said bearing E and a nut, c⁵, upon the upper end of the shaft C' is placed a coiled spring, 100 F, which tends to move the shaft C' endwise through the bearing and to hold the shafts C and C' in alignment with each other. Said bearing E is in the particular form of ma-

- chine shown in Figs. 1 and 2 provided with an interior shoulder, e' , at its lower end, and the screw cap or nut e^5 fits closely within the hollow bearing E in the part of the latter above the shoulder. The coiled spring F is placed around the shaft C' inside of the tubular bearing, which serves to conceal the spring. A cap, e^2 , may be placed over the top of the tubular bearing, to prevent access of dust to the parts and to give a neat finish to the parts. In practice, when the clothes or other articles are placed in the perforated chamber B , they are not always evenly distributed therein, and inasmuch as the cylinder and connected parts tend always to turn about a line or axis of rotation passing through the center of gravity of the parts such axis of rotation is not always coincident with the axis of the shaft when the latter is vertical.
- 20 The tension of the spring F , arranged in the manner set forth, tends to keep the shafts C C' in a vertical position and in alignment with each other, while an inclination of the shaft from the vertical is permitted by the ball-and-socket connection and by the universal joint, which afford a flexible connection between the upper end of the shaft C and the machine-frame, the shaft C' being drawn downwardly against the action of the spring F when the upper end of the shaft C is moved laterally.
- 25 The tension of the spring F may be increased by screwing the nut e^5 farther down the shaft, enabling the lateral movement of the shaft C to be limited or restrained, as desired.
- 30 For actuating the shaft or receptacle, I have herein shown as located at either side of one of the standards near its lower end pulleys G G' , and near the upper end of this standard a pulley, G' . Around these pulleys G G' and the pulley b on the shaft C is placed an endless band or belt. (Not shown in the drawings.) Upon the same shaft, g , that carries the pulley G' , I mount the shift and drive pulleys H H' . A belt passing from the drive-wheel of the motive power to these pulleys H H' furnishes the power to run the machine.
- 35 40 In centrifugal extractors of the kind herein shown the rapidly-revolving loaded receptacle tends, when the receptacle is unevenly loaded, to turn about an axial line passing through its own center of gravity instead of about the axis of the supporting vertical shaft, and in the case of extractors used for drying clothes the departure of the supporting-shaft from the vertical may be considerable. In centrifugal extractors as heretofore made the shaft
- 45 50 has been sustained in a vertical position by means of a plurality of springs acting laterally against it, said springs yielding to allow the shaft to assume an inclined position. Springs applied in this manner have been found objectionable, not only on account of the complicated construction in and increased cost of the machine occasioned by their use,

but for the reason that such springs can seldom be adjusted to act with exactly the same pressure in all directions upon the shaft, 70 so that the shaft is liable to yield more easily in one direction than another with obvious disadvantages in the operation of the machine. I have found that to produce the best results in operation the motion of the shaft should be 75 opposed by little resistance when the receptacle and its load is seeking its own center of rotation, and that the departure of the shaft from its normal position should be restrained by greater and gradually increasing 80 force when said shaft assumes a considerable inclination. In the use of a plurality of laterally-acting springs—such as have been heretofore employed—the springs commonly oppose too great a resistance to the departure 85 of the shaft from the vertical, so that the load is prevented from freely seeking its own center of rotation, and the smooth running of the machine is thereby to a greater or less extent impaired.

90 In a machine constructed in accordance with my invention the shaft is held vertical by a spring or yielding pressure acting in a direction endwise of the shaft and tending to pull it into a vertical position. In a construction of this kind an inconsiderable resistance is afforded to a slight departure of the shaft from the vertical, and the resistance is gradually increased as the shaft assumes a considerable inclination, the tension of the spring 100 exerting itself in a direction which becomes more and more nearly transverse to the shaft as the latter swings outwardly from its normal position. The novel construction herein illustrated, furthermore, not only has the advantage over prior devices in its operation, as 105 above described, but it also has the advantage of great simplicity of construction, rendering the machine much cheaper to build and more easily kept in order.

110 The machine shown in Figs. 1 and 2 illustrates only one embodiment of my invention and the main features thereof, and my invention may be carried out in a number of ways other than the one illustrated in said figures— 115 as, for instance, the main parts of the machine may be inverted, in which case the stationary bearing will be placed at the upper end and the movable or yielding bearing at the lower end of the main shaft.

120 The form of shaft-bearing illustrated and above described I deem the cheapest, most simple, and desirable form, although there are many other forms embraced within the scope of my invention which I also deem practical, simple, and cheap. Two of these forms I have illustrated in Figs. 4 and 5. In both of these latter forms the bars A^3 of the frame of the machine are attached to a tubular bearing, a^3 , in which the shaft C' is mounted, and in each the ball-and-socket joint is used to unite the two shafts C and C' . In the modification illustrated in Fig. 4 the shaft C' is made in two parts, C^2 and C^3 , connected be-

low the bearing a^3 by a familiar form of universal joint, C^4 , the upper part, C^2 , of the shaft being mounted to slide through the bearing a^3 , and being provided with a nut or cap, c^5 .

5 A spring, F' , surrounds the shaft, as before, and tends to keep the shafts in their vertical position by pressing upwardly against the nut c^2 . In Fig. 5 the shaft C' is also made in two parts, the upper part, C^5 , being secured 10 rigidly in the bearing a^3 by a set-screw or other fastening device, while the lower part, C^6 , is connected with the shaft C by means of a ball-and-socket joint. The two parts of the shaft C' are rigidly secured to the ends of a 15 very stiff spiral spring, I , which latter forms, with the two portions C^5 and C^6 of the shaft C , a flexible shaft having one end rigidly secured to the bearing a^3 and the other end movably secured by the ball-and-socket joint to 20 the shaft C . In this latter construction the spring I takes the place of the universal joints or connection and the spring shown in Figs. 1, 2, and 4, and forms both a yielding and flexible connection between the bearing at 25 the upper end of the shaft C and the machine-frame.

As illustrated in Fig. 6, the shaft C' is made in two parts, C^7 C^8 , connected with each other by a universal joint, C^9 . In this instance the 30 upper part, C^7 , of the shaft is constructed to slide in a sleeve or tubular bearing, E' , having flexible connection with the machine-frame by means of an intermediate ring, D' , in the same manner as before described in 35 connection with the shaft C' . (Illustrated in Fig. 1.) A coiled spring, F^2 , located between the sleeve E' and the head c^3 upon the upper end of the shaft C^7 , serves to thrust the shaft upwardly. The lower section, C^8 , of the non- 40 rotation shaft C' is in this instance connected with the shaft C by a bearing and adapted to hold the shafts C^7 and C^8 in alignment with each other. Said connection or bearing is herein shown as formed by means 45 of a cylindrical head, c^4 , attached to the upper end of the shaft C , which head is fitted in a cup-shaped bearing, c^5 , upon the lower end of the shaft C^8 , the head c^4 being held in engagement with the bearing by means of a cap, 50 c^6 , secured to the said bearing c^5 , in the manner clearly illustrated in the drawings.

The construction shown in Fig. 6 obviously affords a means of holding the shaft C yieldingly in its vertical position in the same manner as do the devices shown in the other figures of the drawings.

I claim as my invention—

1. The combination, with a perforated receptacle, of a rotating shaft supporting the 60 same, said shaft being mounted at one end in a bearing which permits inclination of the shaft and which allows rotary but not longitudinal movement of the shaft, a movable bearing engaging the other end of the shaft, and constructed to permit rotary but not longitudinal movement of the shaft, said bearing last mentioned being movable both later-

ally and in a direction toward and from the bearing first mentioned, and a spring acting upon said laterally-movable bearing to thrust 70 or move the said bearing in a direction away from the other bearing of the shaft, substantially as described.

2. The combination of a perforated receptacle, a rotating shaft sustaining the same, 75 said shaft being mounted at one end in a bearing which permits inclination of the shaft, with a movable bearing for the other end of the shaft, having flexible connection with the machine-frame, and a spring applied to the 80 said movable bearing and acting to move the said bearing in a direction away from the other bearing of the shaft, substantially as described.

3. The combination of a perforated receptacle and rotating shaft sustaining the same, 85 said shaft being mounted at one end in a bearing which permits inclination of the shaft, with a second non-rotating shaft having flexible and longitudinally-movable connection 90 with the machine-frame, said non-rotating shaft being in bearing with the other end of the rotating shaft, and a spring applied to the said non-rotating shaft and acting to move 95 said non-rotating shaft endwise in a direction away from the opposite bearing of the rotating shaft, substantially as described.

4. The combination of a perforated receptacle with a rotating shaft sustaining the receptacle, said shaft being mounted at one end 100 in a bearing which permits inclination of the shaft, and a non-rotating shaft united with the opposite end of the rotating shaft by a ball-and-socket joint or its equivalent, said non-rotating shaft having flexible and yielding 105 connection with the frame of the machine, substantially as described.

5. The combination of a perforated receptacle and a rotating shaft sustaining the receptacle, said shaft being mounted at one end 110 in a bearing which permits inclination of the shaft, with a second non-rotating shaft connected with the other end of the rotating shaft by a ball-and-socket joint or its equivalent, said non-rotating shaft having both sliding 115 and flexible connection with the machine-frame, and a spring applied between the non-rotating shaft and the frame and acting to hold 120 said rotating and non-rotating shafts in alignment with each other, substantially as described.

6. The combination of a perforated receptacle and a rotating shaft sustaining the receptacle, said shaft being mounted at one end 125 in a bearing which permits inclination of the shaft, with a second non-rotating shaft connected with the other end of the rotating shaft by a ball-and-socket joint or its equivalent, a bearing for said non-rotating shaft connected with the frame of the machine by 130 a universal joint, and a spring applied between the said bearing and the non-rotating shaft for moving the latter endwise, substantially as described.

7. The combination of a perforated receptacle, and a shaft sustaining the receptacle, with a second non-rotating shaft, a tubular bearing for the non-rotating shaft connected 5 with the frame by a universal joint, said bearing being provided with an interior shoulder at its lower end, and a spring surrounding the shaft within the tubular bearing, said spring being held in place by a nut upon the shaft, 10 substantially as described.

8. The combination of an outer casing or tank, a perforated receptacle within said tank, and a rotating shaft sustaining the receptacle, said shaft being mounted at one end in a 15 fixed bearing which permits inclination of the shaft, with a laterally-movable bearing en-

gaging the other end of the shaft above the receptacle and having movable connection with the machine-frame, a spring applied to move said bearing in a direction away from 20 the opposite shaft-bearing, and a pulley mounted on the said shaft near the fixed bearing, whereby the said receptacle and shaft may be rotated, substantially as described.

In testimony that I claim the foregoing as 25 my invention I affix my signature in presence of two witnesses.

GEORGE N. DOWNS.
